UNITED STATES PATENT OFFICE.

CHARLES L. DE WALT, OF WORCESTER, MASSACHUSETTS, ASSIGNOR OF ONE-HALF TO
WINFRED S. GRIFFITH, OF WORCESTER, MASSACHUSETTS.

OIL BURNER.

Application filed September 9, 1924. Serial No. 736,783.

To all whom it may concern:

Be it known that I, CHARLES L. DE WALT, a citizen of the United States, residing at Worcester, in the county of Worcester and State of Massachusetts, have invented a new and useful Oil Burner, of which the following is a specification.

This invention relates to an oil burner of the type in which air is forced into the furnace around the oil supply to provide a spray of oil. The invention is designed for use either in domestic furnaces or in commercial plants for producing steam or heating in any other way.

The principal objects of the invention are to provide a construction in which a plurality of nozzles direct sprays of oil toward a common point or in crossing streams so that no pilot flame will be necessary, as the several flames will ignite those from the other burners in case of trouble; to provide a construction in which the size of the opening through which the oil passes can be reduced very much over the ordinary practice because the oil and air are preheated; and to provide a burner of higher efficiency than has been possible heretofore.

Reference is to be had to the accompanying drawings, in which

Fig. 1 is a plan of a preferred embodiment of this invention for use in domestic steam or hot water heaters and the like;

Fig. 2 is a sectional view on the line 2—2 of Fig. 1;

Fig. 3 is a side view of one burner on an enlarged scale;

Fig. 4 is a plan of the same;

Fig. 5 is a plan of a modified form of burner for use in larger plants;

Fig. 6 is a longitudinal central sectional view of the same on the line 6—6 of Fig. 5; and

Fig. 7 is a transverse sectional view on the line 7—7 of Fig. 6.

Referring first to the first sheet of drawings, it will be seen that the burner shown therein is of a circular compact form and that it can be inserted in the door of an ordinary domestic furnace, either of the steam or hot water type or even a hot air furnace and located on the grate which can form its sole support, if desired. This burner consists of a round or annular cast iron casing 10 consisting of two parts se-

cured together by screws or bolts 11 through their flat flanges. This leaves an annular space 12 substantially circular in cross-section for receiving the air from an air supply pipe or connection 13. The air is blown in to this passage and has its outlet around the several burners, as will appear.

The oil comes in through a pipe 14 and connections 15 to a pipe 16 located centrally inside the air supply pipe 13 and spaced from the walls thereof. This pipe 16 connects into a circular oil pipe 17 which is located in the center of the circular air space 12 and is held in position by set screws 18 or the like.

From the circular fuel pipe 17 lead a plurality of tubes 19. In this case I have shown four of them, each slanted on an angle and terminating in a small perforated tip. Although the minimum size for such a perforation heretofore has been about $\frac{1}{16}$ of an inch I can use as small a one as that produced by a No. 70 drill, namely about .013" in diameter. These four oil

supplying tubes 19 are surrounded by casings 20 which are mounted on the casing 10 and connected with the air space 12 to constitute nozzles. The nozzles preferably project at an angle of 45 degrees from the horizontal. As they screw into the casing 20 they are adjustable. Each of these nozzles 20 has an exit opening in the end through which the air is forced under pressure, taking the oil with it and spraying it in a fine spray. These parts are mounted on the cast iron casing 10 as indicated and they all converge toward a common point so that their sprays would cross each other.

Each one serves as a pilot light for all the others and three of them might get temporarily clogged at one time and, on account of the fourth flame, they would all burst into flame again immediately upon removal of the cause. In this way no pilot light is needed, thus reducing the expense and difficulty of operating one of these burners. It will be seen that on account of the direction in which the flames are projected from the burners the oil itself is preheated in the oil ring before going through the nozzle and the air is preheated also. On account of this double preheating it can be made to form a perfect spray, of course, by the regulation of the adjustable

nozzles 20.

Referring now to Fig. 5, it will be seen that the burner is of a modified form and is intended for use in larger plants. It consists of a circular cast iron casing 10 having a central opening 21 through which the air supply pipe 16 passes. The casing 10 is provided with a flange 22 which is secured to the door of the furnace.

The burner is supported by a grate 23 which is located on the floor of the furnace. The burner is inserted in the door of the furnace and is secured in place by a screw 24. The air supply pipe 16 is connected to the burner and the oil pipe 17 is also connected to the burner. The burner is designed to be used in a hot air furnace and is supported by the grate 23.

In the form shown on the second sheet of drawings the same principles are observed but it is especially adapted for commercial and manufacturing heating plants. Here the air is introduced under pressure, as in Fig. 1 into an air chamber 30. The liquid fuel from a pipe 31 passes into the interior of the air chamber through a pipe 32 preferably located at the center of the air chamber or pipe 30. The oil or other fuel is supplied to a series of tubes 33 which have perforations at the end. Surrounding each of these oil tubes 33 is an air casing 34 adjustably mounted on the pipe 30 and constituting with the tube 33 a nozzle. Each of these casings 34 has a plurality of projections 35, three being shown, and each has an outlet opening 36 of small diameter communicating with the interior of the chamber 34. The top of the chamber 34 is perforated to let the oil out at the center while the air is blown out at the sides around it and produces three jets crossing each other as before and each serving as a pilot light for the other two in a manner described in connection with Fig. 1. The pipe or chamber 30 can be of any desired length to accommodate the size of the boiler to which it is applied and any desired number of these multiple burners can be applied to it in accordance with the conditions existing.

Although I have illustrated and described only two forms of the invention, I am aware of the fact that modifications can be made therein by any persons skilled in the art without departing from the scope of the invention as expressed in the claims. Therefore I do not wish to be limited to all the details of construction herein shown and described but what I do claim is:—

1. A liquid fuel burner comprising an air chamber adapted to receive air under pressure, a fuel pipe extending into the air chamber, a series of tubes projecting from the fuel pipe outwardly through the wall of the air chamber and each having an opening constituting a burner nozzle, a casing surrounding each of these tubes and communicating with the interior of the air chamber for conducting the air outwardly under pressure around the burner nozzles, the openings of said casings and their air jets being inclined to the horizontal and converging for the purpose of concentrating the currents of air.
2. In a liquid fuel burner, the combination with an air chamber adapted to be connected with a source of air under pressure, a fuel pipe located in said chamber and extending along it, a series of tubes extending from the

fuel pipe through the wall of the air chamber and outwardly therefrom, each having a small perforation in the end, and a series of air casings communicating with the main air casing and each one surrounding a fuel tube, said air casings having means for directing air through the paths of the fuel to spray the fuel, and being inclined to the horizontal and converging to cause the several jets of air to project toward each other. 65 70

3. In a liquid fuel burner, the combination with an endless casing having an air chamber therein connected with a source of air under pressure, an endless fuel pipe located within said casing, spaced from the walls thereof, and adapted to be connected with a source of liquid fuel, a plurality of tubes projecting from the fuel pipe through the wall of the casing and pointed in a direction to direct the fuel from the several tubes in crossing lines, and a corresponding series of casings mounted on the air casing, communicating therewith, surrounding the several tubes and perforated for furnishing a blast of air to the fuel escaping from each tube 80 85 to convert it into a spray.

4. In an oil burner, the combination with a circular air casing having an annular chamber of circular cross-section and connected with a source of air under pressure, a circular fuel pipe located within said casing, spaced from the walls thereof, and adapted to be connected with a source of oil, a plurality of tubes projecting from the pipe through the wall of the casing, said 90 95 tubes being located at an angle between the horizontal and vertical to direct the oil to the center from the several tubes, and a corresponding series of air casings mounted on the annular air casing and surrounding the several tubes for furnishing a blast of air to the oil escaping from each tube to convert it into a spray. 100

5. A liquid fuel burner comprising an air chamber adapted to receive air under pressure, a fuel pipe extending through the air chamber, a series of tubes projecting from the fuel pipe outwardly through the wall of the air chamber and each having an opening in its end constituting a burner nozzle, a casing surrounding each of these tubes and communicating with the interior of the air chamber for conducting the air outwardly under pressure around the burner nozzles, said casings and their air jets being 110 115 inclined to the horizontal for the purpose of concentrating the currents of air.

In testimony whereof I have hereunto affixed my signature.

CHARLES L. DE WALT.
